UNITED STATES PATENT OFFICE

141,487

DESIGN FOR A MERCHANTISE DISPLAY RACK

Leslie H. Burlin, Valparaiso, Ind.

Application March 12, 1945, Serial No. 118,411

Term of patent 7 years

(Cl. D80—9)

To all whom it may concern:

Be it known that I, Leslie H. Burlin, a citizen of the United States, residing at Valparaiso, in the county of Porter and State of Indiana, have invented a new, original, and ornamental Design for a Merchandise Display Rack, of which the following is a specification, reference being had to the accompanying drawing forming a part thereof.

mentally on the top and bottom of the discs are repeated over the entire surface, as illustrated in Figure 3;

Figure 3 is a plan view taken along the line 3—3 of Figure 1 and looking in the direction of the arrows, with part of the transparent top of the display rack broken away to illustrate the subjacent structure visible therethrough.

I claim:

The ornamental design for a merchandise display rack, substantially as shown and described.

LESLIE H. BURLIN.
